UNITED STATES PATENT OFFICE

GEORGE DUCAT, OF ROCHESTER, NEW YORK

GOLF BAG

Application filed April 20, 1932. Serial No. 606,408.

This invention relates to golf bags which are portable and in which the various clubs used in playing golf are carried about the field. The principal object of the invention is to provide a bag of this kind which is light and which is provided with simple and inexpensive means whereby it may be supported on the ground or other convenient place in an upright inclined position while the proper club is selected therefrom and being used by the player.

Another object of the invention is to provide a golf bag at or adjacent its bottom with means for retaining it in fixed position against lateral rolling movement while supported in an inclined position by a rod pivoted thereto adjacent its top and engaging the ground or other support at a point spaced from the bottom of the bag.

Still another object of the invention is the provision of a support for a golf bag comprising a rod pivoted to the bag at its upper end and having a limited swinging movement thereon, a spring retaining clip being secured to the bag adjacent its lower end in the path of the rod to retain the latter in inoperative position.

To these and other ends, the invention consists in the construction and arrangement of parts that will appear from the following description when read in conjunction with the accompanying drawing, the novel features being pointed out in the claim at the end of the specification.

In the drawing:

Fig. 1 is a side elevation of a golf bag illustrating one possible application of the invention;

Fig. 2 is a front elevation of the same showing the supporting rod in inoperative position;

Fig. 3 is an enlarged detail view, partly in section, showing how the supporting rod is mounted on the bag;

Fig. 4 is a transverse section of a bag somewhat enlarged, taken on line 4-4 of Fig. 1 and looking in the direction of the arrows at said line;

Fig. 5 is a detail view of the pivot for the supporting rod;

Fig. 6 is a front elevation of a golf bag illustrating another embodiment of the invention, and

Fig. 7 is an enlarged section taken substantially on line 7-7 of Fig. 6 and looking in the direction of the arrow at said line.

Referring particularly to the drawing and to the form of the invention illustrated in Figs. 1 to 5, the golf bag includes a frame constructed of light metal or other suitable light rigid material, which comprises upper and lower rings 1 and 2 respectively which are connected by rods 3 spaced equidistantly from each other and which serve to space the rings 1 and 2 from each other. Secured to and stretched between the rings 1 and 2 is the body of the bag 4 which may be of canvas or other suitable material provided with a shield or shoe 10 of leather or other suitable material. For convenience in carrying the bag about, it may be provided with shoulder strap and handle of conventional form, as shown in Fig. 1 of the drawing.

Pivotedly mounted on the top of the bag is a supporting member or leg in the form of a rod 5. Said rod 5 may be constructed of tubular metal or other suitable material which is light in weight and is of a length substantially equal to the height of the bag. At its lower end, the leg 5 is pointed to engage the ground or other support so as not to slip thereon but is not sufficiently sharp to penetrate it to any extent, so that it is free at all times to be lifted from the ground in any direction. In order to limit its penetration into the ground, the pointed portion 6 may terminate in an enlarged portion or collar 7.

The upper ring 1 may be formed with a bead at its outer edge and to this end is bent around a core or filler 8 which may be made of metal or suitable fibrous material, and its overlapping lower edges may engage the upper end of the bag 4 between them. A U-shaped clip or bracket 9 is seated on the ring 1 at the front side of the bag, the free ends of which project below the ring 1 and are secured to each other by screws or other suitable means. As shown in the drawing, a suitable filler 11 may be arranged between

the free ends of the clip. Adjacent the free end of the outer arm of the clip 9 are a pair of outwardly projecting ears 12 having alined openings in which a pivot 13 is mounted. At its upper end the rod 5 has an enlarged head or bearing member 14 mounted on the pivot 13 to swing thereon between the ears 12. By this arrangement, the movement of the rod is confined to a substantially vertical plane, as seen in Figs. 1, 2 and 3 of the drawing. In order to lend stability to the bag when supported on the rod 5, as shown in Fig. 1, the block 14 projects above the ears 12 where it is provided with an inclined surface 15, formed by cutting off the inner corner of the block which moves into engagement with the outer leg of the clip 9 when the leg 5 is moved to the Fig. 1 position and limits the movement of the leg away from the bag and lends stability thereto.

Cooperating with the leg 5 to support the bag in the upright position shown in Fig. 1 is a pair of lugs or legs 16 projecting radially from the ring 2 at the bottom of the bag. The lugs 16 are formed on the ends of an arcuate bracket 17 conforming to the curvature of the ring 2 to which it is secured on the front side of the bag by means of screws or other suitable means. When the bag is supported in the inclined upright position of Fig. 1, the legs 16 engage the ground or other support on opposite sides of the plane of movement of the leg 5 and retain the bag against any tendency to roll on the ring in either direction from said plane.

It is desirable to retain the leg 5 in fixed relation to the bag and preferably folded against its side when not in use. For this purpose, a spring clip 18 is mounted on the bag adjacent its lower end in the path of movement of the leg 5. Said clip may be secured to the ring 2 or the bracket 17 by any suitable means such as screws and comprises a pair of curved or bent fingers forming a split ring, the ends of said fingers being bent so as to incline outwardly away from each other. When the leg 5 is swung from the Fig. 1 position to that shown in Fig. 2, it engages the outwardly projecting fingers of the clip which yield in a direction away from each other and spring into engagement with the leg when the latter has entered the ring portion of the clip. Since the rod 5 is relatively light, the clip 18 may be made of such light material that it automatically reacts to receive and retain the leg 5 when the latter is swung toward the bag.

Referring now to the form of the invention illustrated in Figs. 6 and 7, the bag 4', supporting rod 5' and the frame on which the bag is mounted are similar in all respects to that shown in Figs. 1 to 5 except that the frame and bag are D-shaped in cross-section, as clearly shown in Fig. 7. The leg or rod 5' is pivoted at its upper end to a clip 9' mount-

ed on the top of the bag in a manner similar to the mounting of the clip 9 and secured thereto at a point intermediate the vertical edges of the plane side 19 of the bag. At its lower end, the leg cooperates with a spring clip 18' secured to the bag adjacent its lower end, in the vertical plane in which the leg is arranged to swing and intermediate the vertical edges of the flat side of the bag. When a bag of this kind is arranged in the inclined or upright position shown in Fig. 1 of the drawing, the lower or bottom edge of its plane side 19 engages the ground or support in a substantially straight line intersected by the plane of movement of the leg and overcomes any tendency of the bag to roll out of the vertical plane in which the leg 5' swings or moves. It will thus be noted that with this form of bag, the lugs 16 may be dispensed with since their function is performed by the form of the bag itself.

Although the invention has been described with reference to certain details, it will be understood that this application is intended to cover such changes or modifications as come within the spirit of the invention or scope of the following claim.

I claim:

A golf bag comprising a bag portion, a frame in which said bag is mounted, a support pivoted to the frame adjacent its upper end to swing in a vertical plane toward and from the bag, an arcuate plate secured to the frame adjacent the bottom of the bag and having its ends bent outwardly to afford radially projecting lugs which are adapted to engage the ground at points approximating the width of the bag and to cooperate with the pivoted support to hold the bag in an inclined position, and resilient means secured to said plate and intermediate the lugs for retaining said supporting member in an inoperative position adjacent the side of the bag.

In witness whereof, I have hereunto signed my name.

GEORGE DUCAT.
